Primary Examiner — Mimosa De(74) *Attorney, Agent, or Firm* — Greer, Burns & Crain, Ltd.(57) **CLAIM**

The ornamental design for an aircraft seat, as shown and described.

DESCRIPTION

FIG. 1 is a perspective front right view of the aircraft seat embodying the present invention.

FIG. 2 is a front elevational view of the aircraft seat embodying the present invention.

FIG. 3 is a rear elevational view of the aircraft seat embodying the present invention.

FIG. 4 is a left side elevational view of the aircraft seat embodying the present invention.

FIG. 5 is a right side elevational view of the aircraft seat embodying the present invention.

FIG. 6 is a rear right perspective view of the aircraft seat embodying the present invention.

FIG. 7 is a top elevational view of the aircraft seat embodying the present invention.

FIG. 8 is a perspective front left view of the aircraft seat embodying the present invention; and,

FIG. 9 is a rear left perspective view of the aircraft seat embodying the present invention.

The broken lines in the FIGURES represent portions of the aircraft seat that form no part of the claimed design.
